Apollo Richmond of Providence R. I. Assignor to 413
 A. C. Barstow & Co of Providence R. I.
 Letters Patent No. 333. Dated Nov. 12. 1850.

The Schedule referred to in these Letters Patent and making part of the same.

To all Persons to whom these Presents shall come:

Be it Known, That I.

Apollo Richmond of Providence, in the County of Providence, and State of Rhode Island, have invented, or produced a new design for the exterior of a parlor air-tight stove, and I do hereby declare that the following is a full and exact specification of the same, reference being had to the accompanying plates of drawings which clearly exhibit my said new design.

Of the drawings fig. 1, pl. 1, is a front elevation of said stove. Fig. 2, pl. 2, is a plan of the same. Fig. 3, pl. 2, is a horizontal section taken in the plane of the line, A B, fig. 1, pl. 1; and Fig. 4, pl. 3, is a side elevation, with the vase removed. The other side is substantially similar to that represented in fig. 4, with the exception of the draft plate, D: and the back side is substantially similar to the front, with the exception of the space for the discharging flue.

My new design consists firstly of a base or hearth plate, a a a, curved at each corner, with the moulding, b b b & c, about its exterior, and having the narrow channelled space, c c, between the said exterior moulding, b b, and that at d d d & c, ornamented with the diamonds, e e e, surrounding the clustered beak heads, f f f, cast in alto relief, as shown in fig. 1, pl. 1, and figs. 2 & 3, pl. 2.

Secondarily in the ornamented body of the stove having a plinth, g g g, entirely around it with semi-pyramidal ribs cast in alto relief thereon, (as shown in fig. 1, pl. 1, fig. 3, pl. 2, and fig. 4, pl. 3,) the front, side and back plates having a pilaster, h h h & c,

at each end, as shown in the several figures. The front and back plates have two wide concentric gothic arches, $i\ i\ i + k\ k\ k$, between the mouldings of which are the diamonds, $ll\ ll\ + c$, surrounding the clustered beak heads, $m\ m\ m + c$; and the inner gothic arch, $i\ i\ i$, enclosing three smaller gothic arches, $n\ n\ n, o\ o\ o, p\ p\ p$, (in the next size only two arches are used) with the clustered beak heads, $g\ g\ g$, all the said beak heads and mouldings of the arches being cast in alto reliefo, as shown in the drawings. There is a triangular panel, $r\ r$, in each corner, with clustered beak heads, $s\ s$, cast like the others, as shown in the drawings.

The side plates have two concentric gothic arches, $t\ t + w\ w$, and between the mouldings the diamonds, $v\ v\ v$, surrounding beak head clusters, $W\ W\ W$; there are also on these side plates the inner arch, $u\ u$, having clustered beak heads, $x\ x$, and the triangular panels, $y\ y$, and beak heads, $z\ z$, all cast like those before referred to in alto reliefo. Around the top of the stove is a belt ornamented with inverted semi-pyramidal ribs, $a\ a\ a$; cast in alto reliefo.

In the third place my new design consists in the ornamented cap plate, $b\ b$, having the projecting moulding, $c\ c\ c$, within which is a row of diamonds with clustered beak heads, $d\ d$, cast on the belt, $c\ c$. From the inner edge of this belt rises the moulding, $f\ f$, with the semi-pyramidal ribs, $g\ g + c$. The area of the cap plate within the moulding, $f\ f$, is ornamented with the diamonds and beak heads, $m\ m$, arranged in diagonal positions round the raised circles, $n\ n$, ornamented with diverging semi-pyramidal ribs as represented in the drawings.

In the fourth place my new design consists in surmounting the cap plate, $b\ b$, when the movable plate, $h\ h$, is removed, with an ornamented urn, having diamonds and beak heads, $p\ p$, and semi-pyramidal ribs, $q\ q$; cast in alto reliefo in the several positions, on its exterior, shown in fig. 1. Pl. 1, also in the diamond shaped open-work shown in said figure at $r\ r + c$.

Having thus described my new design for the exterior of a parlor air-tight stove, I shall state my claim as follows.

What I claim as my invention or production, and desire to have secured to me by Letters Patent is, the combination of the several ornamented parts of the stove, viz., the base plate or hearth, having the diamonds and clustered beak heads cast thereon, as described, the side and back plates having a plinth with semi-pyramidal ribs, gothic arches, diamonds, beak heads and band at top with inverted semi-pyramidal beak heads, the cap with its circular ornamented areas, $n\ n$, and diamonds surrounding beak heads $m\ m$, and the vase with its exterior orna-

ments of diamonds, clustered beak heads semi-pyramidal ribs and open work diamonds; all the mouldings, beak heads and ribs being cast in alto relief, as herein above described, and represented in the drawings, the whole combination forming an entirely new design for the exterior of a parlor air-tight stove.

Witnesses.
